UNITED STATES PATENT OFFICE.

ARTHUR H. PITNEY, OF WILMETTE, ILLINOIS, ASSIGNOR TO PITNEY-BOWES EXPORT CORPORATION, OF STAMFORD, CONNECTICUT, A CORPORATION OF DELAWARE.

INKING MECHANISM.

1,377,853.

Specification of Letters Patent. Patented May 10, 1921.

Original application filed March 25, 1920, Serial No. 368,701. Divided and this application filed June 1, 1920. Serial No. 385,681.

To all whom it may concern:

Be it known that I, ARTHUR H. PITNEY, a citizen of the United States, residing at Wilmette, in the county of Cook and State 5 of Illinois, have invented certain new and useful Improvements in Inking Mechanism; and I hereby declare that the following is a full, clear, and exact description thereof, reference being had to the accompanying 10 drawings, which form part of this specification.

This application is a division of my application for patent on postage meter and mail marking machine filed March 25th, 15 1920, Serial No. 368,701 (Case 6424). The present invention relates to inking mechanism for mail marking machines and postage meters, for impressing stamps upon envelopes, cards or the like of the type shown 20 and described in my Patents No. 753,207, dated February 23, 1904, and No. 1,273,793, dated July 23, 1918, and in my aforesaid application.

The objects of the present invention are:— 25 to provide an adjustable support for the inking member, whereby it may be moved into position to contact with the printer or out of position to contact therewith; to provide novel means against which the inking 30 roll may be set when out of position to engage the printer, and when so set will properly ink the printer when moved into inking position; and to provide novel means whereby the meter cannot be removed from, or 35 replaced in, the machine unless the inking member is in inoperative position—thus insuring placing of the inking member in operative position before the machine can be effectively operated.

40 The foregoing and other minor objects are attained by this invention, and the accompanying drawings illustrate one practical embodiment of the invention, and I will hereinafter describe the same in detail with 45 reference to such drawings; but the invention is not restricted to the specific constructions and combinations of parts shown, and includes such variations in form, arrangement and combination as fall within the 50 scope of the appended claims.

In said drawings:

Figure 1 is a plan view of the machine.

Fig. 2 is an enlarged detail view showing

the ink supply roller in different positions by means of dotted lines. 55

Fig. 3 is a detail sectional view on line 3—3, Fig. 2.

Fig. 4 is an enlarged detail sectional plan of the trip mechanism.

Fig. 5 is a side view of Fig. 4. 60

General description.

The machine shown in the drawings comprises a feed table 100 having a guide plate 101 and an envelop sealing attachment 102; 65 a feed roller 103, a separator roller 104, which is mounted in a swingable support 105 by which the letters are advanced to forwarding rollers 106 and 107, the latter roller being mounted on a swingable support 108; 70 and these forwarding rollers advance the letter or object to be printed to the trip rollers 21, 22, hereinafter referred to, by which the letters are directed to and between the impression roller 137 and printer 38, hereinafter referred to, and after being postmark-stamped the letters are discharged between rollers 108 and 109 in front of the stacker wheel 110, by which they are stacked 75 in the usual manner on a table or rack 111. 80

The aforesaid parts are all actuated in proper time with the mechanism herein-after to be described but as they form no essential part of the present invention and are not claimed herein, I have not explained 85 or illustrated the same in detail herein.

The trip mechanism.

The trip roller 22 is preferably journaled on a swingable support and guard 15, which 90 has a part 15^a which projects beyond the roller 22, and these parts are normally yieldingly pressed toward the roller 21 by a suitable spring, such as indicated at 22^a in Fig. 1. The shaft of the roller 21 is mounted in 95 fixed bearings opposite the roller 22 and guard 15, and a fence or guide 16 is arranged beside and between the rollers 21 and 22, beside the guard 15, and is slotted to accommodate the rollers 21 and 22 so as not to 100 interfere with their contact with the letter passing between them.

A trip finger 1 is pivoted on a spindle 27 and has a curved head or end 1^a which projects in the path of the letter at the meeting 105 line of the rollers 21 and 22 so that a letter

passing between these rollers, or between the fence 16 and guard 15 will strike this trip finger and will oscillate spindle 27. To spindle 27 is pinned and arm 2 and the trip finger and arm 2 oscillate or move as one piece. The trip finger is normally held in letter engaging position by a suitable spring, such as indicated at 28, arm 2 being arrested by abutting against a stop pin 29 when the trip finger is in normal position.

The arm 2 is adapted to engage the curved and notched end 3^a of a trip link 3; the said curved end being supported and guided in a grooved member 13. The trip link is normally held in position to engage the arm 2 by a spring 20. The other end of trip link 3 is pivoted to one arm 4 of a stop lever which is pivoted on a stud 4^a and which arm 4 is normally held against a stop 18 by means of a spring 19, that thus holds the trip link normally retracted. These parts and their operative connections are more fully described and shown in my aforesaid original application, Serial No. 368,701.

25   *The meter or registering devices.*

The meter for registering the operations of the printer comprises a base 31; a printer 38; and a casing 34 fastened to this base inclosing the registering mechanisms and locking devices therefor; as shown and explained in my aforesaid application, the whole being so constructed that they are removable from and replaceable in the machine as a unit.

35   The printing member or "printer" 38 may be of any suitable kind. For the purpose of postmark-stamping letters it should be provided with suitable dies for printing the stamp upon the letter, and may be provided with canceling lines if desired. The postmark-stamp die may be such, for example, as shown in my patent above referred to, or my Patent No. 753,207; or in Patents No. 1,274,831, and No. 1,273,793.

45   The printer is mounted on a spindle 37, journaled in bearings on the meter; and spindle 37 carries the letter guide wheel 39. These parts may all be constructed and operated as shown and described in my aforesaid application.

55   As shown the top plate of the machine is provided with a horizontally disposed slot into which the base 31 of the meter is slid to place the meter in operative position, indicated in Figs. 1 and 2, the slot having grooves in its sides adapted to be engaged by ribs on the sides of the base 31 of the meter; and when in operative position on the machine the meter is secured by suitable means as described in my said application.

60   When the meter is slid into place in the machine the key 47^a on the lower end of the spindle 37 is adapted to telescope with and enter the slot 20^a in the upper end of the

driven member 20 whereby the spindle and printer will be rotated when the parts are in operative position and the trip mechanism is actuated by the passage of a letter as explained in my said application. 70

The inking mechanism.

The printer 38 may be supplied with ink by any suitable means. I prefer to employ an inking pad or roller 123 (Fig. 1) which is mounted on a swingable bracket or arm 124 rigidly connected to the upper end of a shaft 23 (Fig. 3) suitably mounted in the frame at one side of the meter; so that the inking roller 123 can be turned from the position shown in full lines in Figs. 1 and 2, where it contacts with the printer 38, into the position shown in dotted lines in Fig. 2, where it would not contact with the printer. The inking roller may be held in operative position to contact with the printer 38 by means of a catch 125 having a tooth adapted to engage a notch in the end of the support 124 as indicated in Fig. 2, this latch being controlled by a suitable spring 224.

Fast to the shaft 23 is a cam 14 (Figs. 4 and 5) which cam is adapted to engage the trip-link 3 and move it out of position to be engaged by the arm 2 whenever the ink roller is swung out of position to contact with the printer, so that moving the inking roller out of contact with the printer 38 automatically renders the trip mechanism ineffective; and thus the machine is prevented from being run without inking the printer when it is being used to postmark-stamp letters. Also if it is desired to run the machine merely to seal the letters without printing them the adjustment of the inking mechanism out of the way automatically, through the described devices, renders the trip mechanism and the printer ineffective. 100

110   Preferably the inking roller 123 is adjustably connected to the slide 124 by mounting the inking roller on a slide 127, which is fastened to the support 124 by a thumb screw 128. When the inking roller 123 is turned out of operative position, as indicated in dotted lines in Fig. 2, it may be adjusted into contact with a gage pin 25, which is so fixed in the machine that if the periphery of the inking roller is set up 120 against this gage pin when the support 124 is in the position indicated in dotted lines in Fig. 2, then the periphery of the inking roller 123 will properly contact with the printing surfaces on the printer 38 and 125 properly supply ink thereto when the inking mechanism is turned to operative position, as shown in full lines in Figs. 1 and 2.

130   This gage pin 25 might be removable but I prefer to have it fixed in the machine.

This pin is a simple and efficient device for the purpose described, but I do not consider the invention limited to such pin, as other devices equivalent thereto in function and effect might be substituted therefor within the scope of the invention.

It is desirable to provide means to prevent the removal of the meter from (or replacing it in) the machine without first 10 moving the ink roller out of operative position; and thus render it necessary for the operator to readjust the inking roller each time the meter is replaced in the machine. For this purpose I preferably attach a pin 15 320 to the meter base, at such a point that when the meter is in the machine, said pin lies close against the left end of the fence 16, as indicated in Fig. 2, out of the way, but the inking roller 123 when in operative 20 position lies in the path of pin 320 and consequently if it is attempted to remove the meter from the machine without first adjusting the inking roller into inoperative position (as indicated in dotted lines in Fig. 25) the pin 320 will strike the inking roller as the meter is drawn outward and prevent the complete withdrawal of the meter until the inking roller is moved out of the way. Of course the meter cannot be replaced in 30 the machine unless the inking roller is in inoperative position.

By providing this pin 320, or equivalent devices, in the machine, it becomes necessary to readjust the inking roller to operative position each time the meter is replaced in the machine; and this pin insures first that the machine will not operate until the inking roller is in operative position, and also insures that any possible 40 shrinkage or reduction in the size of the inking roller will be compensated for by the operator adjusting the inking roller against the pin 25, which practically automatically insures compensation for any variation in 45 size of the inking roller, which would naturally be reduced in size by wear.

While I prefer to use the pin 320 as and for the purpose described and it is simple and efficient, I do not consider the invention limited to use of such pin as other devices equivalent thereto in function and effect might be substituted therefor within the scope of the invention.

What I claim is:

55 1. In a machine of the character specified, a printer; an inker; an adjustable support for said inker, whereby it may be moved into position to contact with the printer or out of position to contact therewith; and means for setting the inker when out of operative position so that when so set it will properly ink the printer when moved into inking position.

60 2. In a machine of the character specified, a printer, an inker, and an adjustable support

for said inker, whereby it may be moved into 65 position to contact with the printer or out of position to contact therewith; with a device against which the inker may be set when out of position to engage the printer, so that when so set it will properly ink the printer 70 when moved into inking position.

3. In a machine of the character specified, a printer, an inking roll, and an adjustable support for said inking roll, whereby it may be moved into position to contact with the 75 printer or out of position to contact therewith; with a relatively fixed pin against which the inking roll may be set when out of position to engage the printer so that when so set it will properly ink the printer when 80 moved into inking position.

4. In a machine of the character specified, a printer; an adjustable inker; a removable meter, and a device connected with the meter whereby the removal of the meter is prevented by contact of said device with said inker unless the latter is first moved into inoperative position.

5. In a machine of the character specified, a printer; an adjustable inker; a removable 90 meter; and a pin connected with the meter base whereby the removal of the meter is prevented by contact of said pin with the inker unless the latter is first moved into inoperative position.

6. In a machine of the character specified, a printer, an inker, an adjustable support for said inker whereby it may be moved into or out of operative position; a removable meter; and a pin connected with the meter base 100 whereby the removal from or insertion of the meter in the machine is prevented by contact of said pin with the inker unless the latter is first moved into inoperative position.

7. In a machine of the character specified, a printer; an adjustable inker; a removable meter, a device connected with the meter whereby the removal of the meter is prevented by contact of said device with said inker unless the latter is first moved into inoperative position; and means for setting the inker when out of operative position so that when so set it will properly ink the printer when moved into inking position.

8. In a machine of the character specified, a printer; an adjustable inker; a removable meter; a pin connected with the meter base whereby the removal of the meter is prevented by contact of said pin with the inker unless the latter is first moved into inoperative position; with a device against which the inker may be set when out of position to engage the printer, so that when so set it will properly ink the printer when moved into inking position.

9. In a machine of the character specified, a printer, an inker, an adjustable support for said inker whereby it may be moved into or

out of operative position; a removable meter; and a pin connected with the meter base whereby the removal from or insertion of the meter in the machine is prevented by contact
5 of said pin with the inker unless the latter is first moved into inoperative position; with a relatively fixed pin against which the inker

may be set when out of position to engage the printer, so that when so set it will properly ink the printer when moved into inking position.

In testimony that I claim the foregoing as 10 my own, I affix my signature.

ARTHUR H. PITNEY.
